DISAPPEARING IRONING BOARD

Filed May 15, 1922

Patented Jan. 15, 1924.

1,480,817

UNITED STATES PATENT OFFICE.

HENRY PERCIVAL DIXON, OF LOS ANGELES, CALIFORNIA.

DISAPPEARING IRONING BOARD.

Application filed May 15, 1922. Serial No. 560,935.

To all whom it may concern:

Be it known that I, HENRY PERCIVAL DIXON, a citizen of the United States, and resident of Los Angeles, in the county of Los Angeles and State of California, have invented new and useful Improvements in a Disappearing Ironing Board, of which the following is a specification.

The present invention relates to a combined ironing board and cabinet, and has for its primary object the provision of an improved form of mounting, whereby the board may be adjusted to two heights. The structure herein disclosed is of the character in which the lower panel of the cabinet is hinged to the board and serves as a strut. In addition to the broader objects of this invention, there are certain details of structure, whereby, first, a permanent fastening 15 between the ironing board and the lower panel of the cabinet, the latter being hinged to the cabinet frame, is secured; and second, a fastening means is provided which is readily adjustable to a selected height by 20 the user of the board.

With the above mentioned object and other objects and corresponding accomplishments in view, the invention consists in the novel construction and combination of parts 25 hereinafter described, illustrated in the accompanying drawings and pointed out in the subjoined claims. To more fully comprehend the invention, reference is directed to the accompanying drawing, disclosing one 30 form of my invention, and in which:

Fig. 1 is a perspective view of a fragment of the cabinet showing the lower panel and the ironing board in partially open position; Fig. 2 is a section through the cabinet and board showing the board in open 35 position; and Fig. 3 is a horizontal section showing the board in closed position within the cabinet.

Referring more particularly to the drawing, 4 is a cabinet, preferably of such dimensions that it will readily fit in the wall between the studdings of ordinary and usual building structures. The cabinet is open at the front and provided with an upper 40 hinged door 5 and a lower hinged panel serving as a strut for the ironing board. The side members of the cabinet are each provided with a slot forming ways for guide pins. At the upper end of the slots are offset notches 8 and 9.

Secured by hinges 10 to the lower cross

member of the cabinet frame is the panel 6. The ironing board 11 is secured to the upper end of the panel by means of a triple leaf hinge 12. At the rear the ironing board 60 has guide pins 14 which are disposed to ride in slot 7.

Suppose it is desired to unfold the board into its higher position, the door 5 is opened and the top of the ironing board 11 grasped 65 and pulled outwardly. The guide pins 14 are maintained in the slots 7 until they reach the upper end thereof and are then directed outwardly into the notches 9 by pulling the board forwardly. This positions 70 the rear end of the ironing board at its higher position. To dispose the panel 6 in a corresponding position, it is moved inwardly into position shown in full lines in Fig. 2 so that the middle leaves of the hinges 75 12 are disposed beneath the leaves of the hinges fastened to the board 11. If it is desired to dispose the board in its lower position, the guide pins 14 are directed into the notches 8, and the hinges 12 unfolded so 80 that the middle leaves rest against the ironing board in the position shown in dotted lines in Fig. 2.

It is apparent that the lower panel serves as a closure panel for the cabinet and also 85 as strut for the ironing board. As a strut it is adjustable to two positions. All of the parts of the apparatus are permanently fastened together, thereby providing a device which requires a minimum of manipulation 90 to close and open it into adjusted position.

What I claim is:

1. In a device of the class described, the combination of a cabinet having horizontal lateral slots at different heights, a panel pivoted at its lower end to the lower portion of said cabinet to be swung on a horizontal axis and for closing the lower portion thereof, an ironing board having 100 guide pins at its rear slidable in said cabinet and arranged to be disposed in said slots, a triple leaf hinge securing the upper end of said panel to said ironing board so that said panel may be disposed to support said board at different places intermediate its ends and thereby to support said ironing board at varying heights.

2. In a device of the class described, the combination of a cabinet having vertical 110 ways in the sides with lateral extensions at different heights, a panel pivoted at its lower

2
end to the lower portion of said cabinet to be swung on a horizontal axis and for closing the lower portion thereof, an ironing board having glide pins at its rear slidable in said ways, a triple leaf hinge securing the upper end of said panel to said ironing board so that said panel may be disposed to

support said board at different places intermediate its end and thereby to support said ironing board at two different heights. 10

In witness that I claim the foregoing I have hereunto subscribed my name this 8th day of May, 1922.

HENRY PERCIVAL DIXON.
